UNITED STATES PATENT OFFICE.

CHARLES F. IRONS, OF PROVIDENCE, RHODE ISLAND.

DESIGN FOR A BADGE.

SPECIFICATION forming part of Design No. 19,191, dated July 2, 1889.

Application filed June 3, 1889. Serial No. 312,962. Term of patent 3½ years.

To all whom it may concern:

Be it known that I, CHARLES F. IRONS, a citizen of the United States, residing at Providence, in the county of Providence, in the 5 State of Rhode Island, have invented and produced a new and original Design for a Badge, of which the following is a specification, reference being had to the accompanying drawing, which shows in front view the 10 badge, and forms a part hereof.

The leading features of my design consist of a triple cross, on the central portion of which is a Maltese cross surrounded by a narrow ring or circular band, all ornamented and 15 marked as hereinafter specified.

A triple cross is displayed having its central portion concealed by a Maltese cross. A plain narrow margin extends all along the exposed edges of the triple cross, while the remaining 20 parts which are exposed present space for suitable inscriptions, as shown. A narrow band in the form of a circle extends from the upper to the lower arms of said cross, and is divided into four equal sections that present spaces for 25 suitable inscriptions, as shown. A Maltese cross is shown whose length and breadth are equal to the inner diameter of said circular band, each of the arms of which cross is represented as having one corner overlying said 30 circular band and its other corner underlying said circular band. The center of said Maltese

cross is a circle, outside of which is a circular band concentric with said central circle. The upper arm of the Maltese cross is ornamented with a horizontal sword having a party-colored ribbon hanging therefrom, on which ribbon is suspended a Maltese cross, in the center of which, within a circle, are displayed a passion cross and crown. The left-hand arm of the Maltese cross shows a group consisting of a 35 helmet and crossed swords, also a monogram and a group consisting of a passion cross, crown, and triangle. The lower arm of the Maltese cross has a Latin cross with ornamented arms and a Maltese cross resting 40 thereon, in the center of which is the figure of a mounted knight. The right-hand arm of the Maltese cross shows in one group a Latin cross, a small passion cross thereon, a 45 crown, a shield, and crossed swords, and in another group a Maltese cross having a triangle at its center. All of the arms of the Maltese cross have ornamental chasing along 50 their edges and on the parts adjacent to the central circles of the cross. 55

I claim—

The design for a badge herein described and shown.

CHARLES F. IRONS.
